(57) **CLAIM**

The ornamental design for a multi-dose dispenser with dial retractor, as shown and described.

DESCRIPTION

FIG. 1 is a front, left top perspective view of a multi-dose dispenser with dial retractor showing my new design;

FIG. 2 is a front view thereof;

FIG. 3 is a left side view thereof;

FIG. 4 is a right side view thereof;

FIG. 5 is a bottom view thereof; and,

The rear view is flat and unornamented and forms no part of the claimed design.

The broken lines shown in the drawing disclosure are for illustrative purposes only and form no part of the claimed design.
